UNITED STATES PATENT OFFICE.

ANTHELME BOUCHER, OF PARIS, FRANCE, ASSIGNEE TO LA SOCIÉTÉ LE FER, OF GRENOBLE, FRANCE.

PLANT TO MANUFACTURE IRON BY ELECTROLYTIC MEANS.

Application filed March 17, 1925. Serial No. 16,235.

To all whom it may concern:

Be it known that I, ANTHELME BOUCHER, a citizen of the Republic of Switzerland, residing at Paris, France, have invented 5 certain new and useful Improvements in a Plant to Manufacture Iron by Electrolytic Means, of which the following is a specification.

As is well known to persons skilled in the art, in order to obtain good results in electrolytically manufacturing iron by deposition on a cathode, the operation must be conducted under certain clearly defined conditions which have been described in my prior Patent No. 1,086,132, granted February 3, 1914, and in patent to Auguste Bouchayer, No. 1,516,326, granted November 18, 1924.

The said conditions or requirements are as will be remembered, the following ones:

1st. Constant circulation of the ferrous salt solution around the cathode.

2nd. Maintenance of the said solution at a constant degree of concentration.

25 3. Maintenance of the said solution at a constant temperature.

4. Maintenance of the said solution in a physicochemical condition calculated to ensure good depolarization.

30 5. And lastly rotation of the cathode.

The object of the invention is to provide a plant to manufacture iron by electrolytic means and on an industrial scale that will meet the above-recited requirements in practice.

Besides the general arrangement, the plant is characterized by a system of peculiar dispositions or of special devices designed and combined in view of effectuating the required conditions and of fostering in the best possible way the electrolytic process.

The improved plant comprises a series of electrolyzing troughs, each of which is provided with a rotary cathode and in which a continuous circulation of the electrolyte is obtained in the manner hereinafter described.

In order to make the invention more clearly understood, there has been illustrated, as an example, an embodiment thereof in and by drawings appended hereto and wherein:

Figure 1 shows diagrammatically a plant

constructed according to the invention and some details of which are illustrated by the other figures.

Figure 2 is a sectional view of a device suitable for oxidizing the electrolyte.

Figure 3 shows, also sectionally, a heater designed to keep the solution used at the desired constant temperature.

Figure 4 is a section of a neutralizing and decanting device.

Figures 5 and 6 are details of one of the electrolyzing troughs fitted with its rotary cathode and show also the manner in which the said cathode is rotated as well as the way in which the electric current is supplied thereto.

In all the figures the same reference numerals denote the same parts.

As apparent from the drawings the plant comprises a series of electrolyzing troughs 1 having each a rotary cathode and parallelly mounted between two channels, to wit: 75 an electrolyte-distributing channel 2 and an electrolyte-returning channel 3.

The electrolyte arriving by channel 2 is distributed into each of the troughs 1 through a pipe 4 made of some insulating material and the said electrolyte, after circulating around the cathode, is discharged at the other end of the trough through another insulator pipe 5 leading to the return channel 3.

Devices are provided to put at will one or several of the troughs out of circuit.

The return channel 3 discharges into a collecting tank 6; which constitutes the lowest point of the circuit and from which the said electrolyte is constantly raised by an elevator or pump 7 which brings it into various apparatus indicated at 8—9—10—9'—10', the functions of which will be herein-after explained, and wherethrough the electrolytic solution successively circulates by gravity to come out of the last apparatus 10' through a conduit 11 that leads it to the distributing channel 2. The whole plant is so designed as to ensure by gravity constant circulating of the solution constantly supplied from the lowest point of the circuit and lifted again to the topmost point thereof by the elevator 7. On the drawing the arrows show the direction along which the solution circulates.

Besides the various electrolyzing troughs 1, the plant comprises a trough 12 called the "regulating reservoir" which is mounted, like the troughs 1 themselves, parallelly between channels 2 and 3 and wherein the electrolyte, led in by an insulator pipe 13 and led out by another insulator pipe 14, circulates in a continuous manner in the same way as in the electrolyzing troughs; a pipe 15 permits suitable additions to be made to the solution in the said regulating reservoir.

This "regulating reservoir" or trough 12 may be located at any point of the circuit and be given any form.

15 As will be readily realized the general arrangement of the plant permits to be ensured one of the operating requirements hereabove reminded, to wit: constant circulating of the electrolyte around the cathode in each of the electrolyzing troughs.

It will now be explained how the plant meets the various other above indicated requirements.

First of all, maintenance of the electrolytic solution at a constant degree of predetermined concentration is readily effected by means of suitably regulated additions of liquids, which additions may be made at any point of the circuit but preferably in the regulating reservoir 12 through, for instance, a pipe 13 provided for this purpose.

In order to keep the electrolytic solution at a constant temperature (the third hereabove mentioned requirement) care should, 35 in the first place, be taken to avoid losses of heat by suitable calorific insulation of the various parts of the plant: containers, apparatus, conduits, ducts, channels, buildings, etc.

40 Furthermore, at one or several points of the circuit, the solution should be suitably re-heated by any suitable agent: steam, hot gases, electricity, fuel. Such re-heating may, for instance, be accomplished in one or several of the heating apparatus comprised in the series of devices indicated at 8, 9, 10, 9' and 10'. In the embodiment shown two reheaters 9 and 9' are provided, and I have illustrated, as an example, in Figure 3, such a heater where the solution, entering at 16 and leaving at 15, is heated by some hot fluid circulating through a coil 18.

The fourth requirement—"maintenance of the solution in a physico-chemical condition productive of good depolarization"—may, in the plant shown, be achieved by various means used either separately or in combination.

60 As is well known the first thing to be done consists in keeping the liquid suitably oxidized. For this purpose I may oxidize the solution either by injecting air or oxygen with or without steam, or I may add oxygen 65 by means of the apparatus indicated at 8, through which the solution is passed and an

embodiment whereof is illustrated by Figure 2, or again, by delivering oxygen in any form into the regulating reservoir 12. In Figure 2, 19 and 20 indicate, respectively, the inlet and outlet of the solution into and from the apparatus or tank, and 21 indicates the inlet for the air or oxygen.

70 Persons skilled in the art are aware that such oxidation may be obtained by the formation of oxygen resulting from the use of insoluble anodes. I may therefore effect this oxidation in the trough 12 by arranging insoluble anodes therein.

75 Since an excess of oxygen admitted into the liquid will produce an acidity noxious to electrolysis, there is occasion to neutralize such acidity. This operation will be effected by making the liquid pass through a layer of iron-filings in receptacles or tanks included in the circuit, say at 10 and 10', and the details of which will be hereinafter described.

80 As is well known, there become formed in the course of operations insoluble substances, such as muds and slimes, an excess of which it is necessary to eliminate. Part of these substances may be removed in the neutralizing tanks 10 and 10' and the remainder will be eliminated, if need be, in the regulating reservoir 12. The neutralizers 10 and 10' 90 are designed as shown by Figure 4; they comprise a layer of iron-filings 22 through which passes the electrolytic solution which enters at 23, follows the path indicated by the arrows and comes out at 24. During its 95 passage through the filings the solution at the same time that it becomes neutralized, leaves on the said filings the greater part of its insoluble mud contents.

100 The muds extracted either in the neutralizers or in the regulating reservoir are collected and afterwards washed and treated so as to recover their ferrous salt contents; which salt after being either concentrated or diluted to a suitable degree, may be added 105 to the electrolyte by means of the pipe 15 which discharges into the regulating reservoir 12. The rotation of the cathode in each trough and its electric connection may be effected by the devices illustrated by Figure 5.

110 In this figure is seen at 25 the cathode supported on bearings so arranged as to permit it to be readily withdrawn for collecting the iron formed by electrolytic deposit.

I utilize a collector 26 constituted by a shaft which is connected at one of its ends with a suitable source of motive power and the other end of which is coupled to the cathode by means of a sleeve 27 that transmits the rotary motion.

115 The stator with which such shaft or rotor is associated is connected with the negative pole of the electrolyzing current. The lat-

ter is transmitted to the collector either by means of brushes or by means of a liquid conductor (mercury, for instance).

Lastly, the current is transmitted from 5 the collector 26 to the cathode 25 by means of a ring made in two parts clamped by a collar, the whole marked 27.

In Figure 6 the anode is seen at 28.

It is to be clearly understood that the 10 above described embodiment has been given merely as an example and that the right is reserved to introduce any constructional modification without being deemed to depart from the scope of the invention.

15 The number and the arrangement of the various apparatus or devices 8—9—10—9'—10' may be varied; each of them may also be duplicated so as to permit "interchange" or to serve as a "spare" if required.

20 These various devices may be separate, as shown, or grouped so as to constitute a single unit.

I claim as my invention:

1. A plant for the continuous production 25 of electrolytic iron, comprising an electrolyzing trough provided with an anode and a cathode and adapted to circulate an electrolyte gravitally therethrough; a pipe for supplying the electrolyte to said trough; a 30 collector tank; piping for delivering spent electrolyte from the trough to said tank by gravity; apparatus interposed between said tank and the inlet end of the supply pipe and connected to the same for revivifying the spent electrolyte; and a pump 35 for constantly withdrawing the electrolyte from the collector tank and forcing it into and through said apparatus and thence into the supply pipe.

40 2. A plant for the continuous production of electrolytic iron, comprising a battery of electrolyzing troughs arranged side by side, each trough having an anode and a cathode 45 therein and adapted to circulate an electrolyte gravitally through it; a supply pipe located above and at one side of the battery of troughs and provided with a series of distributing pipes, one for each trough; a channel located below and at the other side 50 of the battery of troughs and into which they constantly discharge spent electrolyte; a collector tank into which said channel discharges by gravity; apparatus interposed between said tank and the inlet end of the 55 supply pipe and connected to the same for revivifying the spent electrolyte; and a pump for constantly withdrawing the elec-

trolyte from the collector tank and forcing it into and through said apparatus and thence into the supply pipe.

60 3. In a plant for the continuous production of electrolytic iron, the combination, with an electrolyzing trough provided with an anode and a cathode, piping for supplying an electrolyte at one end of the trough, 65 and piping for discharging the spent electrolyte at the other end thereof; of apparatus interposed between the supply and discharge piping and connected to the same for revivifying the spent electrolyte; and a 70 pump for constantly forcing the spent electrolyte from the discharge piping into and through said apparatus and thence into the supply piping.

75 4. A plant, according to claim 3, in which the revivifying apparatus comprises an oxydizing tank, at least one re-heater connected with the discharge side thereof, and at least one device for neutralizing and purifying the re-heated electrolyte.

80 5. A plant according to claim 3, in which the cathode in the electrolyzing trough has connected to it a device for continuously rotating it.

85 6. A plant according to claim 3, in which the cathode is removably mounted in the electrolyzing trough to permit its bodily removal therefrom, and has releasably coupled to it a device for continuously rotating it.

90 7. A plant according to claim 3, in which the cathode in the electrolyzing trough has connected to it a device for continuously rotating it; and in which the revivifying apparatus comprises an oxydizing tank, at least one re-heater connected with the discharge side thereof, and at least one device 95 for neutralizing and purifying the re-heated electrolyte.

100 8. A plant according to claim 3, in which the cathode in the electrolyzing trough has a collector for rotating it; said collector embodying a shaft adapted to be connected at one end with a source of driving power, a clutch connection between the other end of said shaft and the cathode to transmit the rotation of the latter to the former, and a stator associated with said shaft and connected with the negative pole of the source of current; and means for transmitting the current from the collector to the cathode.

105 In testimony whereof I affix my signature.

ANTHELME BOUCHER.
